ATTORNEYS

UNITED STATES PATENT OFFICE.

SIMON ELBAUM, OF BAYONNE, NEW JERSEY.

PAJAMAS.

1,148,367.

Specification of Letters Patent.

Patented July 27, 1915.

Application filed September 30, 1914. Serial No. 864,261.

To all whom it may concern:

Be it known that I, SIMON ELBAUM, a citizen of the United States, and a resident of Bayonne, in the county of Hudson and 5 State of New Jersey, have invented a new and Improved Pajamas, of which the following is a full, clear, and exact description.

The invention relates to wearing apparel, and its object is to provide a new and improved pajamas arranged to permit convenient vertical adjustment of the trousers relative to the coat, to insure a proper fit of the trousers as to the length, and to enable the dealer to keep fewer sizes on hand as the 10 trousers can be fitted to persons of different height and girth.

In order to accomplish the desired result, use is made of a coat and trousers, the coat being provided at the inside with vertical 20 rows of fastening members, and the trousers being provided exteriorly with single fastening members each adapted to engage one of the fastening members in the corresponding row of fastening members of the coat 25 to wholly support the trousers from the coat and to allow of wearing the trousers higher up or lower down to suit the height of the wearer.

A practical embodiment of the invention 30 is represented in the accompanying drawings forming a part of this specification, in which similar characters of reference indicate corresponding parts in all the views.

Figure 1 is a perspective view of the pajamas as applied and showing the coat in open position; Fig. 2 is an enlarged front elevation of the trousers; Fig. 3 is an enlarged side elevation of one open side of the coat; Fig. 4 is an enlarged sectional plan 40 view of the connection between the trousers and the coat at one side; and Fig. 5 is a similar view of the connection between the trousers and the coat at the front.

The pajamas consist of trousers A and a 45 coat B, of which the trousers A are provided with a waistband C and front flaps D, D' adapted to be connected with each other at the waistband by a single buttonhole and button or a similar fastening device E, of 50 which one member, however, projects on the front of the waistband C, as shown in the drawings. The trousers A are further provided at the sides with darts to gradually narrow the trousers from the hips upward 55 to the waistband C, as plainly shown in

Figs. 1 and 2, and at one side of the upper ends of the darts F are exteriorly arranged buttons E' or similar fastening members.

The coat B is adapted to be opened and closed at the front and is for this purpose 60 provided with overlapping front flaps G and G', of which the front flap G is provided with fastening members H such as button holes, adapted to engage fastening members H', such as buttons, arranged exteriorly on the flap G' so that when the coat is closed the flap G' is the inner flap, while the flap G is the outer flap (see Fig. 5). The inner flap G' is provided with an additional vertical row of fastening members I in the 70 form of buttonholes, any one of which is adapted to be engaged by the button E on the front of the trousers A, it being understood that the said fastening members I are located near the outer edge of the flap G', 75 as plainly indicated in the drawings. The inner face of the coat B is provided at the sides with vertical strips J each provided with a vertical row of buttonholes or similar fastening members K, any one of which is 80 adapted to engage the button or other fastening member E' on the corresponding side of the trousers A.

In using the pajamas, the wearer first puts 85 on the trousers A and closes the flaps D, D' by the fastening members E, and then the wearer dons the coat B and connects the side fastening members E' with the corresponding fastening members K on the strips J so 90 that the lower ends of the trousers are disposed the desired distance above the wearer's feet. The wearer now fastens the corresponding fastening member I to the fastening member E, and then fastens the flaps G, G' together by the fastening members H, H'. 95 It will be noticed that by the arrangement described the trousers A are wholly supported from the coat B and the trousers can be suspended while up or lower down to suit the height of the wearer by engaging the 100 fastening members E and E' with corresponding fastening members I and K on the coat B. Pajamas constructed as shown and described may then be worn by a person of more or less height and girth and hence the 105 dealer in pajamas need not keep a large number of sizes in stock in order to fit his patrons.

As is well known, the trousers of pajamas as heretofore constructed are provided with 110

draw strings, bands and the like for fastening the trousers to the waist of the wearer, but by these means the trousers are closely fitted around the waist and do not provide 5 the desired freedom as the trousers constructed and worn according to my invention above described.

The lower end of the coat B is provided at the sides with inverted V-shaped cut-out 10 portions to widen the coat, and the strips J terminate at their lower ends on the apex of the said cut-out portions L to reinforce the same and prevent the coat from being torn at this point.

15 Having thus described my invention, I claim as new and desire to secure by Letters Patent:

1. Pajamas comprising a coat and trousers having a waistband provided with a 20 button at the front center and at each side, the coat having overlapping front flaps provided with fastening devices permitting opening and closing the coat, the inner flap having a vertical row of button holes, of 25 which one is adapted to engage the front trouser button, and button hole flaps secured to the inner face of the coat at each side thereof, each flap being provided with a vertical row of button holes adapted to en-

gage a corresponding side button to support 30 the trousers at the sides.

2. Pajamas, comprising a coat and trousers, the trousers having a waistband provided with a button at the front and one at each side, the said coat having overlapping 35 front flaps provided with fastening devices permitting opening and closing the coat, the inner flap having a vertical row of buttonholes, of which one is adapted to engage the said front trouser button, and buttonhole flaps secured to the inner face of the coat at the sides thereof, each flap being provided with a plurality of buttonholes located one above the other and adapted to engage a corresponding side button on the 40 waistband of the trousers, the said coat having an inverted V-shaped cut-out portion at the lower edge of each side, the said buttonhole flaps terminating at their lower ends on the apex of the said cut-out portions. 50

In testimony whereof I have signed my name to this specification in the presence of two subscribing witnesses.

SIMON ELBAUM.
